United States Patent Office

Des. 218,007
Patented July 14, 1970

218,007

BUCKLE

Etienne Aigner, New York, N.Y., assignor to Villager Industries, Inc., a corporation of Delaware

Filed Sept. 18, 1968, Ser. No. 13,600

Term of patent 14 years

Int. Cl. D2—08

U.S. Cl. D2—427

Fig-3

Fig-2

Fig-1

Fig-5

Fig-4

FIG. 1 is a front elevational view of a buckle, showing my new design;

FIG. 2 is a side elevational view thereof;

FIG. 3 is a top plan view thereof;

FIG. 4 is a bottom plan view; and

FIG. 5 is a vertical sectional view taken on the line 5—5 of FIG. 1.

The broken lines in FIG. 1 represent a trademark.

I claim:

The ornamental design for a buckle, substantially as shown and described.
